UNITED STATES PATENT OFFICE.

GRAY WASHINGTON JOHNSTON, OF NEW YORK, N. Y.

AUTOMATIC OPERATING MECHANISM FOR ELECTRIC-RAILWAY SWITCHES.

SPECIFICATION forming part of Letters Patent No. 727,147, dated May 5, 1903.

Application filed July 16, 1902. Serial No. 115,869. (No model.)

To all whom it may concern:

Be it known that I, GRAY WASHINGTON JOHNSTON, a citizen of the United States, residing at New York city, in the county of New York and State of New York, have invented new and useful Improvements in Automatic Operating Mechanism for Electric-Railway Switches, of which the following is a specification.

10 My invention relates to operating mechanism for electric-railway switches.

As is well known, it is common to operate the switches of electric railways by hand; but this requires the attendance of an operator at each intersection of the main and branch rails of the system, which greatly adds to the operating expenses of the road.

15 It is the purpose of my invention to provide means whereby the switches of electric railways may be operated automatically from the car, and thereby dispense with the services of the operators now provided for this purpose.

20 The invention consists of an electromagnet whose armature is operatively connected with the switch-rail, a normally open shunt-circuit between the line conductors including said magnet, an electric switch for closing said shunt-circuit, and an electromagnet operatively connected with said electric switch and in circuit with one of the line conductors.

25 The invention also consists in certain features and details of construction and combinations of parts, which will be hereinafter more fully described and claimed.

30 In the drawings forming part of this specification, Figure 1 is a sectional view of the switch-operating rod or bar and the solenoids for controlling the movement thereof. Fig. 2 is a sectional view of the rotary electric switch and the solenoid for operating the same, and Fig. 3 is a diagrammatic view of the device and the circuit connections between the various operative parts thereof.

35 Like reference numerals indicate like parts in the different views.

40 My invention has been illustrated in connection with an underground electric-railway system; but it will be obvious that the same is equally well adapted for use in connection 45 with an overhead system. The main-track rails 1; the branch rails 2, the pivoted switch-point 3, and the line conductors 4 and 5 may

all be of the usual form and construction with this exception, that the conductor-rail 4 is broken just in advance of the switch, the two parts 4 and 4^a thereof being electrically connected together in any suitable manner, as by the wire or conductor 6. The conductor-rail 4 is provided with an extension 7 just beyond the point of connection therewith of the wire or conductor 6, the said extension lying in line with the two parts 4 and 4^a of conductor-rail.

45 Operatively connected with the switch-point 3 and also, if desired, with the slot-switch is a longitudinally-movable horizontally-disposed rod or bar 8. This bar is usually pivoted to a lever 9, having a socket in its upper end for the reception of a handle-bar 10, by means of which the switch-point 50 may be thrown by hand. According to my construction, however, I extend the bar 8 outwardly between two pairs of magnets 11 and 12 11^a and 12 12^a. These magnets have been shown in the form of solenoids, a common 55 core 13 being provided for the magnets 11 and 12 and a common core 14 being provided for the magnets 11^a and 12^a. Secured to the cores 13 and 14 is a cross-bar 15, which is attached at a point intermediate its ends to 60 the rod or bar 8. By this construction it will be seen that when the magnets 11 and 11^a, which are in series with each other, are energized the rod or bar 8 will be moved longitudinally in one direction to operate the 65 switch-point 3 in a corresponding direction, and that when the magnets 12 and 12^a, which are in series with each other, are energized the rod or bar 8 will be moved longitudinally in the opposite direction, with the result that 70 the position of the switch-point 3 will be reversed.

75 The magnets 11 and 11^a and 12 and 12^a are arranged in shunt-circuits between the line conductors 4 and 5, and these circuits are 80 adapted to be automatically closed by means of an electric switch 16, automatically operated by a magnet 17. The switch 16 has been shown in the form of a rotary switch and the magnet 17 in the form of a solenoid. The 85 said solenoid is in circuit with the conductor-rail 4 and the extension 7 thereof, the said circuit including the wire 18, leading from the conductor 4, and the wire 19, leading to

the extension 7. The said solenoid has been shown as in series between the conductor 4 and extension 7, although it is obvious that the same may be arranged in multiple arc, if desired.

- 5 The rotary switch 16 consists of a disk 20 of insulating material, mounted to turn upon a shaft 21, fixed in position upon the framework 22. Secured to and carried by the disk 10 are the rings 23 and 24 of conducting material. Also secured to the disk 20 and projecting outwardly from the periphery thereof are the lugs or projections 25, 26, and 27, the same coöperating with and adapted to engage the spring-pressed contact-point 28, connected by the wire 29 with the wire 18, heretofore referred to. The lugs 25 constitute dead contact-points, the same being out of electrical connection with any other parts of 15 the device. The lugs 26, however, are electrically connected to the ring 23, and the lugs 27 are electrically connected with the ring 24. The lugs 26 and 27 are alternately arranged around the periphery of the disk 20, and between each of the lugs 26 and the adjacent lug 27 one of the lugs 25 is arranged. The lugs 25, 26, and 27 are arranged in the manner above described at regular intervals around the periphery of the disk 20.
- 20 It will of course be obvious that instead of making the disk 20 of insulating material it may be made of conducting material. If made of the latter material, however, it will of course be necessary that the rings 23 and 24, as well as the lugs 25, be insulated therefrom and that the lugs 26 and 27 be also insulated therefrom, but electrically connected with the rings 23 and 24, respectively. It will also be obvious, as will hereinafter appear, 25 that the lugs 25 may be dispensed with altogether. The core 30 of the solenoid 17 extends through an upright 31 and has surrounding it a coil-spring 32, which bears against said upright and against a head or disk 33 on the end of said core. The spring 32 resists the inward movement of the core 30 when the solenoid 17 is energized and tends to move said core to its normal outward position when the solenoid 17 has been deënergized. The said 30 core 30 has a clutch connection with the rotary switch 16, so that when said core is moved in one direction through the action of the solenoid 17 it will rotate the switch 16 through an arc equivalent to the distance between one of the lugs 25 and the next adjacent lug 26 or 27, and when said core is moved in the opposite direction through the action of the spring 32 it will rotate the switch 16 through an arc of equivalent length. The 35 particular form of clutch shown by me, but to which I do not desire to limit myself, consists of a ratchet-wheel 34, secured to the disk 20, a pair of arms 35 36, pivoted to the shaft 21 and extending in opposite directions from said shaft, pawls 37 38, carried, respectively, by the arms 35 and 36 and adapted to engage the teeth of the ratchet-wheel 34 and

the links 39 40, pivotally connected to the core 30 and to the outer ends of the arms 35 and 36, respectively.

site that which it formerly occupied and the switch will be set for the passage of the car from the main to the branch track. In the meantime, however, the car will have 5 passed beyond the extension 7, and the circuit through the solenoid 17 and that through the solenoids 11 and 11^a will be broken. The switch-point 3 will remain in the position to which it has been moved; but the core 30 of 10 the solenoid 17 will be moved through the action of the spring 32 to its normal outward position. During this movement of the core 30 through the action of the clutch described the disk 20 of the rotary switch 16 will be 15 moved so as to separate the lug 26 from the contact-point 28 and bring in engagement with said contact-point the next adjacent lug 25, which is a dead contact-point. If a car approaching the switch desires to pass in the 20 direction for which the switch is set, it is merely necessary for the motorman to cut off his motor and move by the momentum of his car past the extension 7 of the conductor-rail 4. Neither one of the circuits above traced 25 will then be closed, and consequently no action will take place on the switch-point 3. In the event that the car stops on the rail 7, it is merely necessary in order to reverse the 30 position of the switch to turn the current on or off as often as it is desired to change the position. If the switch-point, however, be set for the motorman to continue to draw current 35 from the conductor-rails until after the extension 7 of the conductor-rail 4 is passed. When contact takes place between the current-collector on the car and the extension 7 40 the circuit is closed, as before, through the solenoid 17, and the latter is energized. When so energized, the core 30 is drawn inwardly toward the solenoid 17, and through the clutch referred to the disk 20 of the electric switch 16 is moved so as to separate the 45 lug 25 from the contact-point 28 and move the adjacent lug 27 into engagement with said contact-point. A shunt-circuit between the conductor-rails 4 and 5 is then closed over the 50 following path: wires 18 and 29, contact-point 28, lug 27, ring 24, brushes 41, wire 42, solenoids 12 and 12^a, and wires 43 and 44. The solenoids 12 and 12^a will then be energized, and the cores 13 and 14 thereof will be 55 moved inwardly toward said solenoids. The result of this action will be to move the rod or bar 8 and the switch-rail 3 connected therewith in a direction opposite that in which they were formerly moved, so that the switch will 60 be set for the passage of the car along the main-track rails 1. As soon as the car passes beyond the extension 7 the circuit through the solenoid 17 is broken, as well as that through the solenoids 12 and 12^a. The switch- 65 rail 3 will remain in the position to which it was moved; but the core 30 of the solenoid 17 will be returned to its normal outward posi-

tion through the action of the spring 32. When so moved, the core 30 through the clutch described will rotate the disk 20 of the 70 switch 16 so as to separate the lug 27 from the contact-point 28 and bring about the engagement of the adjacent lug 25 with said contact-point. It will thus be seen that the only thing necessary to be done by the motor-man in order to operate the switch 3 in one direction or the other is to leave on the current through the motor of his car while approaching said switch. If it be desired to pass in the direction for which the switch 3 80 is set, the only action necessary by the motor-man is to cut off the current through his motor as he approaches said switch. The operation of the device is automatic throughout, and by the use of the same the services of attendants or operators at each switch may be 85 dispensed with.

I have described the lugs or contacts 25, 26, and 27 on the disk 20 of the switch 16 as projecting beyond the periphery of said disk. It 90 is obvious, however, that these lugs or contacts may be otherwise disposed without departing from the nature or spirit of my invention. It is also obvious that for the particular form of rotary switch shown and described I may substitute any other form of rotary switch or, indeed, may employ a switch which is not mounted for rotation. I do not therefore limit myself to any of the details of construction herein shown and described, except as defined by the appended claims.

Having now described my invention, what I claim as new, and desire to secure by Letters Patent, is—

1. The combination with a railway-switch 105 and the line conductors of an electric-railway system, one of which is made in sections, which sections are electrically connected with each other on opposite sides of said switch, of a conductor extension located between and in line with the sections of the sectional conductor, an electromagnet for operating said switch, a normally open shunt-circuit between said conductors including said magnet, a magnet in circuit between said extension 110 and one of said conductor-sections, and means actuated by the latter magnet for automatically closing said shunt-circuit.

2. The combination with a railway-switch 120 and the line conductors of an electric-railway system, one of which is made in sections, which sections are electrically connected with each other on opposite sides of said switch, of a conductor extension located between and in line with the sections of the sectional conductor, an electromagnet for operating said switch, a normally open shunt-circuit between said conductors, including said magnets, an electric switch controlling said shunt-circuit, and an electromagnet in circuit between said extension and one of said conductor-sections for automatically actuating 125 said electric switch and thereby closing said shunt-circuit.

3. The combination with a railway-switch and the line conductors of an electric-railway system, one of which is made in sections, which sections are electrically connected with each other on opposite sides of said switch, of a conductor extension located between and in line with the sections of the sectional conductor, an electromagnet for operating said switch, a rotary electric switch, a shunt-circuit between said conductors normally broken through said electric switch and including said magnet, and an electromagnet in circuit between said extension and one of said conductor-sections for automatically actuating 15 said electric switch and closing said shunt-circuit.
4. The combination with a railway-switch and the line conductors of an electric-railway system, one of which is made in sections, which sections are electrically connected with each other on opposite sides of said switch, of a conductor extension located between and in line with the sections of the sectional conductor, an electromagnet for operating said 20 switch, an electric switch having contacts thereon, a fixed contact adapted to be engaged by the contacts on said switch, a shunt-circuit between said conductors normally broken through said electric switch, the same 25 including said magnet and said fixed contact, and a magnet in circuit between said extension and one of said conductor-sections, for operating said electric switch, to cause the engagement of one of the contacts thereon with 30 said fixed contact and thereby close said shunt-circuit, as and for the purpose set forth.
5. The combination with a railway-switch and the line conductors of an electric-railway system, one of which is made in sections, which sections are electrically connected with each other on opposite sides of said switch, of a conductor extension located between and in line with the sections of the sectional conductor, two electromagnets whose armatures are connected with said switch for operating 40 the same in opposite directions, an electric switch having alternately-arranged contacts thereon, a fixed contact adapted to be engaged by the contacts on said switch, shunt-circuits between said conductors normally broken through said electric switch, one of which includes one of said magnets, one set 45 of the contacts on said electric switch, and said fixed contact, a magnet in circuit between said extension and one of said conductor-sections for rotating said electric switch to cause the successive engagement of the contacts thereon with said fixed contact and thereby alternately close said shunt-circuits, and means for rotating said electric switch to break the engagement between said contacts when the latter magnet is deenergized, as and for the purpose set forth.
6. The combination with the line conductors of an electric-railway system, and a rail-switch, of two electromagnets whose armatures are connected with said switch for operating the same in opposite directions, a rotary electric switch having alternately-arranged contacts thereon, a fixed contact, adapted to be engaged by the contacts on said switch, shunt-circuits between said conductors normally broken through said electric switch, one of which includes one of said magnets, one set of the contacts on said electric switch, and said fixed contact, and the other of which includes the other of said magnets, the other set of contacts on said electric switch and said fixed contact, and a magnet in circuit between said extension and one of said conductor-sections for operating said electric switch, to cause the successive engagement of the contacts thereon with said fixed contact, and thereby alternately close said shunt-circuits, as and for the purpose set forth.
- 65 6. The combination with a railway-switch and the line conductors of an electric-railway system, one of which is made in sections, which sections are electrically connected with each other on opposite sides of said switch, of a conductor extension located between and in line with the sections of the sectional conductor, two solenoids, a common core therefor connected with said switch for operating the same in opposite directions, an electric switch having alternately-arranged contacts 70 thereon, shunt-circuits between said conductors normally broken through said electric switch, one of which includes one set of said contacts and one of said solenoids, and the other of which includes the other set of 75 said contacts and the other of said solenoids, and a magnet in circuit between said extension and one of said conductor-sections for operating said electric switch to close one or the other of said shunt-circuits, as and for the 80 purpose set forth.
7. The combination with a railway-switch and the line conductors of an electric-railway system, one of which is made in sections, which sections are electrically connected with 85 each other on opposite sides of said switch, of a conductor extension located between and in line with the sections of the sectional conductor, two electromagnets whose armatures are connected with said switch for operating the same in opposite directions, a rotary electric switch having alternately-arranged contacts thereon, a fixed contact, adapted to be engaged by the contacts on said switch, shunt-circuits between said conductors normally 90 broken through said electric switch, one of which includes one of said magnets, one set of the contacts on said electric switch, and said fixed contact, and the other of which includes the other of said magnets, the other set of contacts on said electric switch, and said fixed contact, and the other of which 95 includes the other of said magnets, the other set of contacts on said electric switch, and said fixed contact, a magnet in circuit between said extension and one of said conductor-sections for rotating said electric switch to cause the successive engagement of the contacts thereon with said fixed contact and thereby alternately close said shunt-circuits, and means for rotating said electric switch to break the engagement between said contacts when the latter magnet is deenergized, as and for the purpose set forth.
8. The combination with the line conductors of an electric-railway system, and a rail-switch, of two electromagnets whose armatures are connected with said switch for operating the same in opposite directions, a rotary electric switch having alternately-arranged contacts thereon, a fixed contact, adapted to be engaged by the contacts on said switch, shunt-circuits between said conductors normally broken through said electric switch, one of which includes one of said magnets, one set of the contacts on said electric switch, and said fixed contact, and the other of which includes the other of said magnets, the other set of contacts on said electric switch, and said fixed contact, a magnet in circuit with one of said conductors for rotating said electric switch to cause the successive 105

engagement of the contacts thereon with said fixed contact, and a spring acting in opposition to the latter magnet for rotating said electric switch to break the engagement between said contacts when the latter magnet is deenergized, as and for the purpose set forth.

9. The combination with the line conductors of an electric-railway system, and a rail-switch, of two electromagnets whose armatures are connected with said switch for operating the same in opposite directions, a rotary electric switch having alternately-arranged contacts thereon, a fixed contact, adapted to be engaged by the contacts on said switch, shunt-circuits between said conductors normally broken through said electric switch, one of which includes one of said magnets, one set of the contacts on said electric switch, and said fixed contact, and the other of which includes the other of said magnets, the other set of contacts on said electric switch, and said fixed contact, a solenoid in circuit with one of said conductors, a core therefor having a clutch connection with said electric switch, for rotating the same to cause the successive engagement of the contacts thereon with said fixed contact and thereby alternately close said shunt-circuits, and a spring acting upon said core, in opposition to said solenoid, for rotating said electric switch to break the engagement between said contacts when said solenoid is deenergized, as and for the purpose set forth.

10. The combination with a railway-switch and the line conductors of an electric-railway system, one of which is made in sections, which sections are electrically connected with each other on opposite sides of said switch, of a conductor extension located between and in line with the sections of the sectional conductor, a pair of electromagnets operatively connected with said switch, an electric switch, two normally open shunt-circuits between said extension and the other conductor, including respectively said magnets, and a magnet in circuit with said extension and the adjacent conductor-section, the latter magnet being operatively connected with said electric switch for successively closing said shunt-circuits, as and for the purpose set forth.

11. The combination with a railway-switch and the line conductors of an electric-railway system, one of which is made in sections, which sections are electrically connected with each other on opposite sides of said switch, of a conductor extension located between and in line with the sections of the sectional conductor, a pair of solenoids, having a common

core connected with said switch for operating the same in opposite directions, a rotary electric switch having alternately-arranged contacts thereon, a fixed contact adapted to be engaged by the contacts on said switch, shunt-circuits between said conductors normally broken through said electric switch, one of which includes one of said solenoids, one set of the contacts on said electric switch and said fixed contact, and the other of which includes the other of said solenoids, the other set of contacts on said electric switch and said fixed contact, a solenoid in circuit with said extension and the adjacent conductor-section, the core of the latter solenoid being connected with said electric switch for rotating it, to cause the successive engagement of the contacts thereon with said fixed contact and thereby alternately close said shunt-circuits, and means for rotating said electric switch to break the engagement between said contacts, when the latter solenoid is deenergized, as and for the purpose set forth.

12. The combination with a railway-switch and the line conductors of an electric-railway system, one of which is made in sections, which sections are connected with each other on opposite sides of said switch, of a conductor extension located between and in line with said sections, a pair of solenoids, a common core therefor operatively connected to said switch, a rotary electric switch comprising a disk, a pair of conducting-rings thereon insulated from each other, and two sets of contacts on said disk, electrically connected respectively to said rings, a solenoid in circuit between said extension and the adjacent conductor-section, a core therefor, a clutch connection between the latter core and said disk, a spring for moving the latter core in opposition to the solenoid to which it belongs, a contact adapted to be engaged by the contacts on said disk, electrical connection between the same and said sectional conductor, and circuit connections between said rings and the other conductor of the system, the same including respectively those solenoids whose common core is operatively connected with said rail-switch, as and for the purpose set forth.

In testimony whereof I have hereunto set my hand in presence of two subscribing witnesses.

GRAY WASHINGTON JOHNSTON.
